UNITED STATES PATENT OFFICE

MARSHALL W. HANKS, OF MADISON, WISCONSIN

LIQUID CONDUCTOR HEATER

Application filed February 27, 1930. Serial No. 431,712.

This invention relates to improvements in liquid conductor heaters and its purpose is to provide improved means for reducing the electric shock hazard incident to the operation of such devices. Liquid conductor heaters of the type referred to commonly comprise a vessel containing a pair of spaced electrodes which are adapted to be connected by a liquid conductor, such as water, which is heated by the passage of current therethrough, with resulting vaporization, until finally the entire quantity of liquid is vaporized with the result that the flow of current is automatically shut off, although the electrodes remain electrically alive, assuming that the electrical conductors leading to the device remain connected to the source of supply, which is the usual condition when the liquid conductor is completely vaporized. One side of the electric supply circuit is commonly grounded and if the operator happens to stand upon a damp surface and touches the wet surface of the vessel during its operation or after the current has ceased to flow due to the evaporation of the liquid, there is likelihood of shock which, while not ordinarily dangerous, tends to retard the development of the practical use of liquid conductor heaters.

The principal object of the present invention is to provide a liquid conductor heater in which there is greater safety from electric shocks than has been possible in the types of liquid conductor heaters heretofore on the market. A further object is to provide a liquid conductor heater adapted for use in an electric circuit having one side grounded and with which, when the electrodes are properly connected to the circuit, the danger of shock is entirely eliminated, while the danger of shock, if the electrodes are improperly connected in the circuit, is no greater than it was in the types of liquid conductor heaters heretofore known. Other objects of the invention relate to various features of construction and arrangement which will appear more fully hereinafter.

The nature of the invention will be understood from the following specification taken with the accompanying drawing in

which one embodiment is illustrated. In the drawing,

Figure 1 shows a central vertical section through one form of liquid conductor heater with the circuit connections illustrated diagrammatically;

Fig. 2 shows a horizontal section taken on the line 2—2 of Fig. 1; and

Fig. 3 shows a horizontal section taken on the line 3—3 of Fig. 1.

As illustrated in the drawing, the invention is embodied in a liquid conductor heater comprising a vessel 10 formed of porcelain or other suitable insulating material which has formed integrally therewith a downwardly extending annular flange 11 adapted to rest upon a table or other support 12. On the upper surface of the bottom wall 13 of the casing there is mounted a plate electrode 14 in the form of an annular ring which extends around the central projection 15 formed on the bottom wall. A pair of terminal posts 16 are secured to the underside of the electrode 14 and extend downwardly through apertures in the bottom wall 13, with which apertures they have a fluid tight connection so that the liquid conductor contained within the vessel 10 will not escape. Extending upwardly through the projection 15 is an externally threaded terminal post 17 which is threadedly engaged at its upper end by the central hub portion 18^a of another plate electrode 19, which is in the form of a circular flat plate having formed therein a plurality of apertures 19^a, and which rests at its outer edge on an annular shoulder 20 which is formed on the inner surface of the wall of the vessel. The electrode 19 is thus spaced from the lower electrode 14 and is adapted to engage the shoulder 20 when in its normal position.

An electric conductor 21 leading from the source of supply is passed through an aperture 22 in the side of the flange 11 and is connected to one of the terminal posts 16 by means of a clamping nut 23. Another electric conductor 24, forming the opposite side of the electric circuit, and having a ground connection as shown diagrammatically at 25, is connected to the other electrode through a

downward extension 17^a of the terminal posts which is engaged by a clamping nut 26. The extension 17^a of the central post 17 is engaged at its lower end by a nut 27 of insulating material having a reduced portion 27^a which rotatably engages an aperture formed in the central part of a plate 28. This plate seats against an annular shoulder 29 formed on the underside of the vessel 10 and thus forms an enclosed chamber 30 within which the exposed metal contacts and parts of the conductors 21 and 24 are mounted, it being understood that the parts of the conductors 21 and 24 which extend outwardly from the vessel to the aperture 22 are suitably insulated from each other and from surrounding objects.

The space 31, above the upper electrode 19, forms the heating chamber in which a vessel 20 containing material to be cooked, for example, is adapted to be mounted and this container for the material to be cooked is adapted to be heated by the steam rising upwardly from the space between the electrodes 14 and 19, due to the vaporization of the liquid conductor which establishes the electric circuit between these electrodes. A measured quantity of the liquid conductor is ordinarily placed in the vessel 10 to establish the electric circuit between the electrodes 14 and 19 and as this liquid conductor is vaporized, the steam rises upwardly through the apertures 19 and a portion thereof condenses on the walls of the chamber 31 so that the surface of the vessel adjacent the upper part of the heating chamber is more or less damp, both during the operation of the device and after the flow of current has been cut off by the practically complete vaporization of the measured quantity of liquid.

After the liquid has been evaporated to substantial dryness, even though there is still some moisture on the interior surface of the vessel, the danger of shocks with the connections shown, is eliminated due to the fact that the upper electrode 19 is in direct contact with the damp surface of the vessel through the annular shoulder 20 and, since the electrode 19 is connected to the grounded side 50 of the line, there can be no shocks, even though the operator be standing upon a damp surface. Should the device be incorrectly connected, that is, if the connections to the electrodes be reversed so that the lower electrode 14 is connected to the grounded side of the line, the danger of shock is no greater than it is in the types of devices heretofore known in which no means have been furnished for establishing a communication with the damp surface of the vessel to prevent a flow of current from the ungrounded electrodes. In the present invention, the flow of current from the lower ungrounded electrode 65 is intercepted by the engagement with the annular shoulder 20 of the upper grounded

electrode and thus this flow of current cannot continue upwardly over the interior wet surface of the vessel surrounding the heating chamber 31.

Although one form of the invention has been shown and described by way of illustration, it will be understood that it may be constructed in various other embodiments within the scope of the appended claims.

I claim:

1. A liquid conductor heater comprising a vessel adapted to contain a liquid conductor, a pair of spaced electrodes mounted in said vessel to be connected by said liquid conductor, an electric circuit having one side thereof grounded and having its terminals connected to said spaced electrodes, and means for causing the current passing over the damp surface of said vessel from one electrode to be intercepted by the other electrode connected to the grounded side of the line.

2. A liquid conductor heater comprising a vessel adapted to contain a liquid conductor, a pair of spaced electrodes mounted in said vessel and adapted to be electrically connected by said conductor, and an electric circuit having one side of the line grounded and having its terminals connected to said electrodes, the electrode connected to the grounded side of the circuit being arranged above the other electrode and being in direct contact with the interior surface of said vessel.

3. A liquid conductor heater comprising a vessel adapted to contain a liquid conductor, a pair of spaced plate electrodes arranged in superimposed relation in the bottom of said vessel, the uppermost electrode being perforated, an electric circuit having one side of the line grounded and having its grounded terminal connected by a direct metallic connection to the said uppermost electrode and the other terminal connected to said other electrode, and an annular shoulder formed on the interior surface of said vessel and normally contacting directly with said uppermost electrode.

4. A liquid conductor heater comprising a vessel adapted to contain a liquid conductor, an electrode mounted in the bottom of said vessel, another perforated electrode mounted above and spaced from said first-named electrode, an electric supply circuit having one side thereof grounded, said circuit having its grounded terminal connected by a direct metallic connection to said upper electrode and its other terminal connected to said lower electrode, and an annular shoulder formed on the inner wall of said vessel and engaging said upper electrode.

5. A liquid conductor heater comprising a vessel adapted to contain a liquid conductor, an electrode mounted in the bottom of said vessel, a perforated electrode mounted above and spaced from said first-named electrode, an electric supply circuit having one side

thereof grounded, a terminal post connected to the grounded side of said circuit and extending upwardly through said vessel with its upper end directly connected to said perforated electrode, said circuit having the other side thereof connected to said lower electrode, and an annular shoulder formed on the inner wall of said vessel and contacting with the outer edge of said upper electrode.

In testimony whereof, I have subscribed my name.

MARSHALL W. HANKS.
